HYDRAULIC SPRING HANGER

Edward R. Hinckle, Dorchester, Mass.

Application November 21, 1951, Serial No. 257,619

8 Claims. (Cl. 248—317)

1

The present invention relates to a hanger for use more particularly in railway cars, trucks and other types of vehicles for hanging sides of beef and other large quarters of meat in shipment.

The invention however has other applications, wherein heavy articles are to be suspended while in motion from beams, brackets or the like or from any support to which the article of the present invention may be attached.

The invention is more particularly applicable to the suspension of sides of beef and meats in railway cars. Up to the present time, when beef is shipped in railway cars the beef is hung from the beam by a hook which passes through the beef and which simply is hung over the beam by means of a U shaped bracket. Using this type of suspension, it frequently happens that the beef falls off the hook on to the floor of the car and as a result the railway company becomes responsible for a damage claim because of the damage to the side of the beef. These claims occur regularly and are a great cost to the railroad companies.

The reason for the beef falling off the hook is due to a number of reasons. In the first place the hook tears its way through the beef or the hole made by the hook becomes sufficiently enlarged so that as the beef shakes around, it may shake off the hook. Secondly the hooks often become dislodged on the beams and fall off. It may also be noted that considerable damage may happen to the beef by the tearing action of the hook in the beef as well as by the beef falling off the hook.

The applicant has determined that the falling of the beef off the hook and the falling of the hook off the beam may be avoided by the proper design of the hook suspension to which the present invention particularly relates.

In the present invention, the suspension means comprises a hydraulic spring suspension hanger in which the shock of the up and down motion of the hook is distributed and absorbed and in which the swinging motion of the hook itself is eliminated. The hydraulic suspension is such that the shock is absorbed both in the upward motion and in the downward motion of the hook.

An additional feature of the present invention is that the suspension is comparatively cheap and inexpensive and may be readily mounted on a beam in the ordinary railway car or it may also be mounted by a suitable wall bracket on a side wall or roof of a car.

2

The hanger may be provided with an oil medium which however will not leak out through the suspension hook.

Other and further advantages of the present invention will be more readily understood in connection with the specification set forth below when read in connection with the drawings illustrating an embodiment of the invention, in which:

10 Figure 1 shows a section in elevation of the hanger, and

Figure 2 shows a top view of Figure 1 with the cover removed.

In the arrangement indicated in the drawings, 15 the hanger 1 may be mounted on a beam 2 which may be a beam in a railway car or other transporting vehicle.

The hanger 1 comprises a housing 2 which may be rectangular in shape as indicated in the figures, conforming in width to the width of the beam. The housing 2 has four side walls 3, 4, 5 and 6, a bottom 7 and a top cover 8 which may be removable and which may be secured tightly over the ends of the side walls by any suitable means. The bottom 7 of the housing or case is provided with a plurality of upstanding bosses 9 arranged symmetrically with the longitudinal and transverse axes of the housing. As indicated in the drawings there are eight such bosses each of which serve as a base of the support for the ends of the coiled springs 10 which extend upward perpendicular to the base. These coiled springs 10 are covered at their top by a plate 11 which is provided with a number of downwardly extending bosses 12, one for each top end of the coiled springs. At the axis of each of the coiled springs are rods 13, which are secured at the centers of the bosses 9 either by threading into a hole as shown in Figure 1 or

30 by some other suitable method. These rods 13 extend upward through the center of the coiled springs through a clearance hole in the top plate 11 through rings 14 about the rods and are capped by the nuts 15. The rings 14 may be threaded to the rods and a lock washer 16 may be provided between the ring 14 and the nut 15 if desired. However the combination of the two threaded members, the ring 14 and the nut 15 should be sufficient to hold the nut firmly in

35 place under vibration which may occur in the motion of the vehicle. Each of the springs 10 are placed under approximately the same tension by adjustment of the position of the plate 11 and the rings and nuts 14 and 15 respectively.

40 45 50 55 The plate 11 is mounted with its plane normal

to the vertical axis of the housing so that as the plate 11 is moved up or down, it will have a slight clearance around its periphery abutting the walls of the housing.

At the center of the base wall 7 of the housing, there is provided an upstanding well or sleeve section 17 normal to the base. This sleeve 17 extends approximately half-way to the housing and at the top has connected to it a flexible tube or collar 18 made of rubber, neoprene or other such material. The collar 18 has its lower end tightly clamped about the top of the sleeve or neck 17 by means of the clamping member or ring 19. The collar 18 is preferably of the accordion bellows type which may completely collapse in a downward direction as viewed in Figure 1. The top of the flexible sleeve or collar 18 is carried through an opening in the plate 11 and is provided with a flange extending over the sides of the opening in the plate 11 by means of which it is firmly clamped to the plate by the clamping cap 20. The clamping cap 20 for this purpose is provided with an outwardly extending flange 21 and suitable clamping screws 22 which thread into the plate 11 and hold the flange of the flexible collar 18 firmly against the plate 11. The inside of the clamping element 20 is threaded to receive the eye-bolt 23 which has a long shank 24 threaded at its end into the cap 20. The lower end of the bolt may be provided with a slot 25 designed to permit a pin to move relatively up and down, in the slot. At the base of the beam 2 surrounding the lower end of the shank 24, there is a short collar 27 which may be secured to the beam by screws 29 passing through flanges of the collar. The collar 27 is provided with a diametric hole through which the pin 26 is placed passing through the slot 25 and thereby preventing the shaft from turning after it has once been put in place. If however it is desired to permit the ring 30 at the end of the eye-bolt to swivel, this may be accomplished by providing a swivel joint as diagrammatically indicated at 31.

The housing is preferably filled with a fluid medium, as for instance, an oil 32, somewhat near or up to the bottom of the plate 11. In fact it may be above the plate 11, dependent to some extent on the range of the damping in the initial part of the up and down motion of the eye-bolt. To provide for the proper damping characteristic, the plate 11 has a plurality of holes 33 which should be of such a size, number and so placed to permit the plate 11 to be pulled downward against the spring force under the pull on the eye-bolt and be released so that the motion both downward and upward will be substantially uniformly sufficient to relieve the impact of the hook against the meat. The maximum effect will be gained when the maximum acceleration in either direction is reduced to a minimum. The amount of oil which passes through the holes in the plate will of course be somewhat less if large clearances are permitted between the side walls and the plate 11.

The hanger as indicated in Figures 1 and 2, is provided with end flanges 34 extending outward from the end of the base 7 through which the hanger may be mounted on the beam by means of the screws 35. This of course provides for mounting over a beam, in which case, the eye-bolt 23 will pass through the beam and the hook will engage in the eye 30. The hook should of course be of a closed type so that it will not open except when desired. The hook attached to the

eye 30 may be a permanent hook or it may be a detachable hook.

The mounting as indicated in the figures, with the hanger on top of the beam and the eye-bolt passing through the beam, has proved to be durable and highly usable construction where beams are used to support the hooks and the meat is hung from the hooks.

In other cases however, for side walls or roof mounting, the flange elements will extend from the side walls of the case, or a strap means may be used, whichever may be the more convenient.

The device shown herein may be made of non-corrodable materials, capable of withstanding the effects of cold and moisture. The case, the internal metal elements and eye-bolt as well as the plate and rods may be made of stainless steel. The eye-bolt should have a well finished shank and have a close sliding clearance with the inside of the well 17. If desired the shank of the eye-bolt may have a cap at the top fitting freely within the cap 20, so that it may turn and thereby avoid a swivel joint at the lower end of the shank as illustrated in Figure 1.

Other suitable modifications may be made without departing from the spirit of the present invention.

Having now described my invention, I claim:

1. An hydraulic suspension hanger comprising a casing having side walls and a bottom, a plate within said casing having its periphery extending to the side walls thereof providing a sliding fit between the plate and the side walls of the casing, a plurality of coiled spring means projecting upward from the bottom of the casing and downward from said plates for locating the springs in fixed positions, said springs suspending and supporting said plate within said casing, a plurality of rods, one for each of said springs having one end fixed in the bottom of the casing and the other end extending through said plate, said rods being coaxial with the axis of the coiled springs, means forming a well projecting upward from the bottom of the casing with its axis symmetrically positioned with respect to said casing, a shaft element coaxial with said well and having a sliding fit therein, said shaft element extending upward through said well into said plate, means for fixing the said shaft to said plate, an hydraulic medium filling the casing substantially up to said plate, a flexible compressible elastic sleeve attached at one end to the top of said well and at the other end to said plate for preventing liquids from leaking out of said well, said shaft extending below the bottom of the housing and terminating in a hook cooperative element.

2. An hydraulic suspension hanger comprising a casing, having side walls and a bottom, a plate within said casing having its periphery extending to the side walls thereof providing a sliding fit between the plate and the side walls of the casing, spring suspension means extending between the bottom of the casing and said plate supporting said plate means forming a well projecting upward from the bottom of the casing with its axis symmetrically positioned with respect to said casing, a rod coaxial with said well having a sliding fit therein, said rod extending upward through said well into said plate, means for fixing the rod to said plate, a flexible compressible elastic sleeve attached at one end to the top of said well and at the other end to said plate for preventing liquids from leaking out of said well, a beam on which said hanger is mounted, said beam

being provided with a hole therethrough, said rod extending through said hole through the bottom end of said beam, a collar positioned at the bottom of the beam around said rod and means partly located on said collar and partly on said rod for preventing said rod from rotating to permit it to move longitudinally on itself.

3. An hydraulic suspension hanger comprising a housing having side and bottom walls, a plate parallel to the bottom wall and having a slideable fit with the sides of the housing in a direction perpendicular to said plate, said plate having a plurality of downwardly projecting bosses and said bottom having a plurality of upwardly projecting bosses aligned one with the other in coaxial sets, a coiled spring connected between each set of opposing bosses with the ends of the springs fitting snugly over the respective bosses, a rod for each set of bosses having one end fixed in the boss of the bottom and the other end freely sliding through a hole in the boss in the plate, a shaft extending through the bottom of the housing and fixed to said plate, said shaft being normal to said plate and fixed substantially in the center thereof, said shaft having at its end beyond the housing a hook cooperating element and an hydraulic fluid within said housing having a level substantially not lower than said plate.

4. An hydraulic suspension hanger comprising a casing having side walls and a bottom, a plate within said casing having its periphery extending to the side walls thereof providing a sliding fit between the plate and the side walls of the casing, a plurality of spaced coiled spring means projecting upwards from the bottom of the casing and downward from said plate, said coils being distributed uniformly over the area of the plate, means securing the coils in fixed positions against the plate at one end and against the bottom at the other end, including in part a stud for each coil fixed to the bottom of the casing passing upwards through the coil and through a hole in the plate and means at the end of the stud over the plate for putting initial tension on the plate and each coil, a rod passing through the bottom of the casing upwards to said plate,

means securing said rod to said plate, said rod being symmetrically positioned with respect to said plate and extending normally thereto, and means forming a liquid sealed joint about said rod to prevent liquid from leaking out of said casing at the bottom about the rod, said rod terminating below said casing in a hook supporting member.

5. An hydraulic suspension hanger as set forth in claim 4, having an hydraulic medium filling said casing substantially to said plate.

6. An hydraulic suspension hanger as set forth in claim 4, in which the means forming a liquid joint about said rod comprises means providing a well projecting upwards from the bottom of said casing through which said rod extends, a flexible compressible elastic sleeve sealed at one end to the top of the well and at the other end to said plate surrounding said rod, whereby said rod is free for movement through said well in accordance with the motion of the plate and springs.

7. An hydraulic suspension hanger as set forth in claim 4, in which the means securing the coils in fixed positions comprises in part bosses extending downward from said plate and upwards from said casing about which said coil ends snugly fit.

8. An hydraulic suspension hanger as set forth in claim 7, in which studs fixed in said bosses extending upwards from the bottom of the casing pass through the coils and through holes in the plate with means secured at the ends of the studs over the plate for exerting initial compression on said coil and plate.
